(57) **CLAIM**

The ornamental design for a presentation mouse, as shown and described.

DESCRIPTION

FIG. 1 is a perspective view of a presentation mouse showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a perspective view thereof in use;

FIG. 9 is a perspective view thereof with mouse buttons in the spread position; and,

FIG. 10 is a perspective view thereof with mouse buttons in the spread position and in use.

The hand shown in broken lines is for illustrative purposes only, and forms no part of the claimed design.
